UNITED STATES PATENT OFFICE

162,492

CORNER FURNITURE UNIT

Emil Tarlazzi, Union City, N. J., assignor to Vanguard Furniture Manufacturers, New York, N. Y., a firm

Application August 27, 1949, Serial No. 4,725

Term of patent 14 years

(Cl. D15—11)

To all whom it may concern:

Be it known that I, Emil Tarlazzi, a citizen of the United States of America, and resident of Union City, county of Hudson, State of New Jersey, have invented a new, original, and ornamental Design for a Corner Furniture Unit, of which the following is a specification, reference being had to the accompanying drawing, forming a part thereof, in which

Fig. 1 is a front perspective view of a corner furniture unit, embodying my design in one position of the unit.

Fig. 2 is a front view thereof with the unit in another position with one closet door partly open.

The back surfaces of the cabinets are plain.

I claim:

The ornamental design for a corner furniture unit, as shown and described.

EMIL TARLAZZI.
